DESIGN FOR A SIDING CORNER PIECE

George W. Strunk and George Lehr, Joliet, Ill.,
assignors to The Ruberoid Co., New York, N. Y., a corporation of New Jersey

Application April 11, 1941, Serial No. 100,322

Term of patent 14 years

To all whom it may concern:

Be it known that we, George W. Strunk and George Lehr, both citizens of the United States and both residents of Joliet, in the county of Will and State of Illinois, have invented a new, original, and ornamental Design for a Siding Corner Piece, of which the following is the specification, reference being had to the accompanying drawing, forming a part thereof, in which:

Fig. 2 is a section on the line 2—2 of Figure 1.

The essential feature of our design resides in a corner piece having the specific grouping of large and small irregular blocks of the configuration shown in association with the beading outlining the top, bottom, and lateral edges of each of the blocks and raised above the surface thereof.

We claim:

The ornamental design for a siding corner piece, substantially as shown and described.

GEORGE W. STRUNK.
